DWELLING ASSEMBLED FROM PREFABRICATED UNITS

James H. Kennedy, Lansdowne, Pa., assignor to
Magnesium Cement Laboratories, Inc., Philadelphia, Pa., a corporation of Pennsylvania

Application March 2, 1934, Serial No. 713,664

19 Claims.

(Cl. 72—16)

This invention relates to the construction of small buildings, such as dwellings, from units which are prefabricated and so far finished in the factory that the units may be assembled and erected with a minimum of labor and skill at the site of the dwelling. More particularly, this invention relates to expedients for simplifying the installation or assembly of the prefabricated units or panels which, to a large extent, go to make up the floors, walls, ceilings, and even the roof of a dwelling constructed in accordance with my invention.

In erecting light and inexpensive structures in accordance with my invention, a narrow elongated structural unit is the most important element. I prefer to produce such a unit by first forming a body or core of fibrous material bonded by magnesium-oxy-salt cement such as magnesium-oxy-chloride cement or magnesium-oxy-sulphate cement, or a mixture of oxy-chloride and oxy-sulphate with magnesium. A number of fibrous materials, such as bagasse, cornhusks, straw, wood shavings, chips, and shredded wood (otherwise known as "excelsior") are suitable for this purpose; but I have found that best results are to be obtained by using one of the several grades of "excelsior" such as wood wool, standard excelsior or coarse excelsior. The mixture of aggregate and cementitious material is distributed on a platten and compressed, the pressure being maintained until the cement has set to such a stage that the compressed material will not expand upon release of the pressure.

This body or core of bonded compressed fibrous material is covered on either or both sides by a surface layer or layers of denser material. This denser material is preferably applied after the core has been dried and cured. A typical material for the surface layer, if the same is to be exposed to the weather, is made up as a stucco from a suitable aggregate and magnesium-oxy-salt cement. This stucco, after being applied, may be coated in the factory with a penetrating, water repellent substance.

A typical composition for the surface layer, if the same is to be exposed in the interior of the dwelling, is a mixture of sand, Silex, asbestos, lithopone and a water-proofer and magnesium-oxy-salt cement. These surface mixtures are, in plastic condition, applied to the surface of the core, either by hand or by machinery; and finished in any finish desired; and if the cores are properly made with an open texture, the surface layers will become anchored to the core so that

the unit is practically a homogeneous mass. Suitable panels for my purpose, and a preferred manner of producing such panels are disclosed in my copending application Ser. No. 713,663, filed March 2, 1934. The present invention relates to features of construction which simplify the erection of light buildings, such as inexpensive dwellings, using prefabricated units of the above-described type.

In the accompanying drawings in which I illustrate certain embodiments of my invention for the purpose of illustrating the same,

Fig. 1 is a side view of a light, inexpensive dwelling erected by assembling prefabricated units;

Fig. 2 is a vertical section illustrating the foundation, the floor, a portion of an outer wall, and a portion of a partition wall;

Fig. 3 is a detail view partly in cross-section and partly in end elevation of means for positioning a joist;

Fig. 4 is an end view, partly in section, of a clip for securing a floor panel to the flange of a beam;

Fig. 5 shows in vertical section a modified construction for supporting the ceiling;

Fig. 6 shows in vertical section a further modified construction for supporting the ceiling;

Fig. 7 is a plan view of a bearing plate located at the top of a corner for positioning angularly related panels;

Fig. 8 is a plan view of a rounded corner member.

The dwelling shown in Fig. 1 of the drawings is of the bungalow type having a foundation 10 cast on a footing 11. The foundation 10 is cast with an offset or shelf 13 adjacent the upper portion thereof on which may rest the junior I-beams 15. These I-beams do not extend the full distance from one outside wall to the other, but are somewhat over half this length, being supported intermediate the outside walls by a central foundation 16 with a flat top. As shown in Fig. 2, the foundation 10 has the offset 13 formed in such dimensions that the ends of the I-beams abut against the upwardly projecting portion 18, thus determining the position of the beams or joists longitudinally. Obviously, the I-beams 15 overlap on the central foundation 16.

The I-beams are positioned laterally by the bearing plate and yokes shown in Figs. 2 and 3. The bearing plate 20 is provided with four openings for receiving the legs of two yokes 21. The ends 22 of the legs are provided with means 23

for anchoring the yokes in the foundation 10 and 16. As shown, the anchoring means 23 takes the form of washers and nuts threaded on the ends 22 of the legs of the yokes; but obviously any other suitable form of anchoring means may be used. The legs 22 and anchoring means 23 are embedded in the foundation in the process of casting the same, and the plate 20 accurately positioned to the proper level, grouting being employed if necessary to accurately position the plate 20. The openings in the plate 20 are so spaced that the base flange of the I-beam 15 is received between the pair of yokes with a close fit, the yokes at that time being in the position shown in dotted lines in Figs. 2 and 3. As shown in the drawings, a plate 20 furnished with a pair of yokes 21 is at each end of an I-beam 15 to position the same. When the I-beam has been lowered into place resting on the two plates 20, the yokes are bent inwardly and downwardly over the base flange of the I-beam, as shown by the full line position, to hold the same in position. The yokes 21 are fashioned of steel which can be thus deformed by a press or by blows from a sledge hammer.

It will be noted that the top surface of the upper flange of the I-beam 15 is nearly flush with the top of the upwardly projecting portion 18 of the foundation. For tightness against drafts, it will be desirable to spread packing or cement 25 on top of the portion 18 to receive the outer border of a floor panel 26. One or more bolts 27 cast in the portion 18 extend through openings formed in the panel 26 in such position that when registering with the bolts 27 the outer edge of the panel 26 is substantially flush with the outer face of the foundation 10.

The long dimension of the panel 26 extends transversely of the I-beams or joists 15, and thus runs lengthwise of the foundation 10. A flat clip 28 may be attached to the side edge of a panel 26 by nails or screws driven through openings 28a in the clip into the body or core of the panel. The clip 28, as shown in Fig. 4, has a cleft 28b conforming to the beam flange; and when the clip is so secured to a panel 26 that the cleft 28b receives the flange of a beam 15, the panel is securely held thereto. An additional opening 28c is provided in the clip for attaching the clip to the web of beam, as by wiring.

The panels are of standard construction and provided with a groove 29 in each of the lateral edges. The groove in the inner edge of the panel 26 is made use of for aligning the panel with the adjoining panel 26'. For this purpose, a spline 30 of hardwood or of bonded aggregate of such character as to have high insulating value is received in the mating grooves 29 of the adjoining panels 26 and 26'. Preferably, this spline 30 will be cemented in the groove to make the joint 30 between panels air-tight. With such a form of joint, using a spline which has high insulating value, the floor will be uniformly insulated throughout its area.

The external border of the panel 26 which rests on top of the portion 18 of foundation 10 is closed in by a rustless metal fastener 33 having a rib 34 conforming to the groove 29 and received therein, thus positioning this fastener relative to the panel 26. The lower portion or skirt 35 of the fastener 33 extends down over the packing or cement 25, thus shutting out rain and helping to make the structure tight. The fastener 33 is bent inwardly at the upper corner of the panel 26 and is shaped with a tongue or spline 37 overlying the

upper end of the bolt 27. This spline 37 constitutes a positioning means which is received in a groove in the base of a vertical wall panel 38. The fastener 33 being secured to the floor, its tongue 37 thus positions the panel 38 relative to the floor. It will thus be apparent that by properly positioning the bolts 27 in the portion 18 of the foundation, the floor panels 26 will be positioned without further measurement, and the wall panels 38 will likewise be positioned. This simplifies the assembling of the panels to construct the buildings, by making it necessary to accurately measure only the position of the offset or shelf 13 and the positions of the plate 20 and the bolts 27, after which the floor and side walls of the dwelling can be placed by unskilled workmen. After the floor panels 26, 26', etc. have been laid, the finished floor surface 40, such as hardwood flooring, tile or linoleum, may be laid on top of the panel and secured thereto. Certain types of finish, however, may be placed on the floor panels in the factory so that when these panels are laid, a finished flooring is provided.

In order to make provision for a base board, it is desirable that the metal fastener 33 be extended inwardly under the inner edge of the panel 38 and then upwardly along the face of the wall to a proper height, after which the fastener is bent downwardly to form a base board portion 41. The edge 42 of the fastener may be recurved to form a rounding edge resting on the finished floor 40. The space behind the portion 41 is available for tubing 43 within which the electric light wires may be carried to the usual outlets provided either in the base board or in the wall. The rustless metal fastener 33, because of its shape, can be more easily rolled in two sections, these sections being assembled with the panel 26 so that the edges overlap within the groove in the base of the panel 38. This assembling is carried out in a very simple manner, and skilled labor is largely eliminated. After installation, the exposed joints may be made tight with water-proof compound.

The wall panels 38 are provided with a groove not only in the base but also in the lateral edges. Accordingly, adjoining wall panels 38 are aligned by splines which are cemented in the grooves, just as described in connection with the flooring. Preferably, the vertical joint between adjoining wall panels 38 is pointed up. The outside face of the panel 38 will consist of a material proof against the weather, such as a stucco or artificial stone composition. The inside surface layer of the panel 38 can take such embodiment as fits in with the decorative scheme, whether it be plastering, tiling or other suitable finish. The most suitable material for the core of the panel being a compacted bonded aggregate, preferably fibrous material and magnesium-oxy-salt cement as above described, it is of distinct advantage to use this same cement as the bonding ingredient of the outer and inner surface layers so that the coefficient of expansion of the cement throughout the panel is substantially the same.

There is considerable flexibility in the construction of a dwelling such as above outlined. Certain of the splines may be omitted so as to leave passageways such as the one shown at 46. This passageway consists of the mating grooves 29 in adjoining panels, and is large enough to carry a pair of pipes. In the panels of larger dimensions, half inch pipes or larger can be carried in the passageway 46. Such a passageway may even be provided in the side wall of the dwelling by

omitting a spline. Moreover, where there is a partition formed of such panels, it is a simple matter to omit a part or all of a spline so as to accommodate the piping required for plumbing in a bath room or kitchen.

Partitions can be readily erected at any desired location by simply securing a spline or tongue to the floor. Such a spline as is shown for instance in Fig. 5 at 47 may be nailed, screwed, bolted or secured in any suitable fashion to the floor. The groove in the base of the partition panel engages this spline or tongue so that the partition is accurately positioned. These partitions may, as shown in Fig. 5, be placed on a packing 48 of felt, or on a layer of "Kellgur" (an artificial rubber which is highly resistant to oxidation), rubber or other material which insulates against sound. In this way a sound-proof partition may be erected in a building such as a hospital with minimum expenditure for labor; and there is the possibility of recovering the panels practically intact if it is desired to remove the partition. The spline 47 shown in Fig. 5 is tapered vertically so as to assist in engaging the groove in the base of the panel with this spline, and to make the panel more readily removable. While the base board 49 shown in this figure is entirely exterior of the partition wall, being secured in place by a nail or screw 50, it is obvious that this base board might be formed of sheet metal with an inwardly bent portion to extend into the groove in the base of the partition panel in similar fashion to the base board shown at 41 in Fig. 2.

The insulating layer 42 at the top of the partition prevents the transmission of sound waves between the side wall and the ceiling. The groove 53 in the top of the panel is useful in positioning the panel relative to the ceiling. For this purpose, a bolt 54 is extended through an opening 49 in the ceiling panel 55, with the lower end of the bolt secured in a strip of rigid material 56 which is entered in the groove 53. A head 57 on the projecting end of the bolt 54 secures this assembly to the ceiling panel 55. Prior to assembling, a combined hanger and bearing plate 58 may be slipped in place on the upper end of the partition panel with the inner flange 59 extending down into the groove 53. The hanger 58 may be formed as picture molding for decorative purposes. The strip 56 entered in the groove 53 positions the top of the partition panel relative to the ceiling panel 55.

The ceiling panels 55 may be of standard construction with grooves 61 in the lateral edges 55 thereof to receive a spline 62. Use may be made of the spline 62 for hanging the ceiling from the roof structure, such as the joists or beams 63. For this purpose, the splines 62 may be suspended by wires 64 from the joists 63. With this construction the supporting structure for the ceiling is completely hidden so that there are no battens exposed on the underside of the ceiling.

On the other hand, if for decorative purposes a batten is desirable, a combined spline and hanger 65 may be entered in the mating grooves of adjoining panels. An extension 66 of the spline protrudes from the joint and is shaped as a batten to overlie the joint. Wires 67 hung from the joists or beams suspend the combined spline and hanger 65 from the roof structure, the hanger being caught to the wire by a key 68 or the like. In both of these forms of ceiling suspension, the spline may be cemented in the grooves for added tightness and greater structural strength. If the spline is of insulating material, the ceiling will

have uniform insulating value throughout its area.

In the form of ceiling construction shown in Fig. 6, the panels 70 are aligned by splines 62 which may be of insulating material if desired and cemented in the grooves 61 for greater structural strength. The top sides of the panels 70 are recessed at 72 to receive inverted perforated metal channels or yokes 73. These short perforated channels are cemented in the recesses 72 and thus firmly anchored in the ceiling panels. Wires 74 thrust through the channels 73 suspend the ceiling from the joists or beams of the roof structure.

It is not always necessary to provide a supporting structure for the ceiling, such as the rafters or beams referred to in describing the constructions illustrated in Figs. 5 and 6. Where the room is small, the panels forming the side walls of the room may carry the weight of the ceiling, and even of the roof. In such case, the splines 62 entered in the grooves 61 should be cemented in place to strengthen the structure. 15 20

A bearing plate, such as shown at 76 in Fig. 7, may be placed on top of the side walls at the corner of a room to position the angularly related panels 38 relative to each other. The bearing plate 76 carries aligning means depending into the grooves 77 in the top edges of the panels 38. As illustrated in Fig. 7, the aligning means takes the form of a perforated metal channel 78 depending into the groove 77 from the plate 76. The bearing plate 76 will usually carry sufficient load so that it is improbable that the aligning means would be dislodged from the grooves 77. However, I find it preferable to use cement in the grooves 77 so as to anchor the inverted channels 78 in place in the grooves. In some instances, the aligning means may be punched in a press so as to extend downwardly from the plate 76. Another suitable way is to form the channels 78 separately and weld them to the plate 76.

The outer corner where two panels 38 come together, as in Fig. 8, may be finished by a rounded corner member 80 of polished stainless steel. The arc of the rounded corner member 80 may be about 90°, or slightly more or less. In forming the corner member from a sheet of steel, the sheet may be bent back at 81 so as to provide rounded ends for the member, the flanges being bent across the end faces of the panels 38. One edge of the sheet may be bent in the shape of a channel 83 tightly fitting the vertical groove 84 in the panel. The other edge of the sheet may be bent into a spring clip 85, V-shaped in cross-section. The channel-shaped portion 83 will be pushed into its groove 84 in assembling the member 80 with the pair of panels 38. In so assembling the member 80 with the panels, the clip 85 springs into the groove 84 of the other panels. Cement or water-proof compound may be used to point up the joint behind the rounded ends 81 of the member 80. In addition the channel-shaped portion 83 may be cemented in its groove 84.

The simplicity of construction of a dwelling such as illustrated in the drawings results largely from the use of a panel which adapts itself to use for a variety of purposes as shown. More particularly, the panels may be applied to various uses with considerable flexibility, the grooves in the edges of the panels being particularly advantageous for this purpose. The constructions shown for mounting and aligning the panels reduce the labor costs and provide a durable and attractive structure which is eco- 75

nomical both as to expense of original installation and, due to insulation against both heat and cold, economical from the point of view of up-keep.

5 An important improvement in building construction is furthermore made possible by my invention; in that studding, and in fact either vertical or horizontal reinforcement such as now erected adjacent to or integrally with the usual 10 panels can be entirely eliminated in the building of small dwellings. A wall, which may either be a bearing or a non-bearing wall, can be made up entirely of my improved panels. A part or all of the weight of a superstructure such as a 15 roof or ceiling can be carried by a bearing wall made up entirely of such panels.

While I have illustrated and described certain embodiments which my invention may assume, it will be understood that the invention is not 20 restricted to the particular constructions and arrangements shown but may be variously modified within the contemplation of the invention and under the scope of the following claims.

I claim:

25 1. In combination in a prefabricated dwelling, a structure and a ceiling hung therefrom comprising a plurality of panels with grooves in adjacent edges, and means for supporting said panels comprising a preformed spline cemented 30 in the grooves of adjacent panels and a suspension device connecting the spline and structure.

2. The combination as set forth in claim 1 in which the panels have each a core of compacted bonded fibrous material and at least one 35 surface layer of denser material.

3. In combination in a prefabricated dwelling, a structure, and a ceiling hung therefrom comprising a plurality of panels with grooves in adjacent edges, a spline cemented in the grooves 40 of adjacent panels and a hanger for suspending said spline from said structure.

4. In combination, a structure, and a ceiling hung therefrom comprising a plurality of panels with grooves in the upper sides thereof, channels 45 cemented in said grooves, and means for suspending said channels from said structure.

5. In combination, a structure, and a ceiling hung therefrom comprising a plurality of panels with grooves in the upper sides thereof, said 50 panels having each a core of compacted bonded fibrous material and at least one surface layer of denser material, channels cemented in said grooves and means for suspending said channels from said structure.

55 6. In combination in a prefabricated dwelling, a floor comprising a plurality of panels positioned edge to edge with grooves in the adjoining edges, a spline seated in adjacent grooves and a conduit received in one of said grooves so 60 as to be invisible from above or below the panels said floor being arranged to resist bending strains from loads thereon.

7. In combination in a prefabricated dwelling, a floor comprising joists, a plurality of grooved 65 panels directly supported on said joists edge to edge, means inserted between and held to adjacent panels for securing the panels to the joists, and means for aligning said panels comprising a spline entered in grooves in adjoining edges of 70 adjoining panels.

8. A floor structure comprising a plurality of elongated flat units having a body or core of compacted bonded fibrous material and a layer 75 of covering material on at least one face thereof, a transverse supporting element for carrying

said units flatwise in adjoining relation, and a flat clip inserted between the edges of adjoining units for attaching a unit to the supporting element, said clip being secured by fasteners extending into the body or core of a panel. 5

9. A floor structure comprising a flat unit comprising a body of compacted bonded shredded wood and a layer of covering material on at least one face thereof, a transverse supporting element for carrying said unit flatwise, and a flat 10 clip secured against a lateral face of said unit for attaching the unit in flatwise relation to said transverse supporting element, said clip being secured by fasteners extending into the body or core of a panel. 15

10. In combination in a structure, a plurality of adjoining panels mounted edge to edge, the mating grooves in adjoining panels forming a concealed recess extending longitudinally within the borders of said panels, means for aligning 20 said panels comprising a spline received in one of said longitudinal recesses, and conducting means for fluid received in one of said longitudinal recesses.

11. A wall structure comprising prefabricated 25 structural sections forming a complete wall structure, each section comprising a plurality of spaced-apart layers of bonded aggregate and cement of sufficient thickness to afford material structural strength, said layers being secured together by a less dense and more porous core of 30 bonded fibrous material extending to the ends of the section and having exposed edge portions, the panels having grooves along their lower edges, and a spline device engaging the registering 35 grooves of the successive panels.

12. A wall structure comprising prefabricated structural sections forming a complete wall structure, each section comprising a plurality of spaced-apart layers of bonded aggregate and cement of sufficient thickness to afford material structural strength, said layers being secured together by a less dense and more porous core of bonded fibrous material extending to the ends of the section and having exposed edge portions, 45 the panels having grooves along their lower edges, and a spline device engaging the registering 50 grooves of the successive panels, said spline having a base portion extending beyond a face of a panel.

13. A wall structure comprising prefabricated structural sections forming a complete wall structure, each section comprising a plurality of spaced-apart layers of bonded aggregate and cement of sufficient thickness to afford material 55 structural strength, said layers being secured together by a less dense and more porous core of bonded fibrous material extending to the ends of the section and having exposed edge portions, the panels having grooves along their lower edges, and a spline device engaging the registering 60 grooves of the successive panels, said panels having vertically extending edge grooves with splines secured therein. 65

14. The combination in a floor structure of a plurality of horizontally arranged joists, a set of panels laid edge-to-edge on said joists, each panel comprising a plurality of spaced-apart layers of bonded aggregate of sufficient thickness to afford material structural strength, said layers being secured together by a less dense and more porous core of bonded fibrous material extending to the ends of the section and having exposed 70 edge portions, the adjacent edges of 75

said floor panels being grooved and splines secured within the registering grooves thereof.

15. The combination in a prefabricated structure, of a floor portion and a wall portion co-acting therewith, said portions each being formed of prefabricated structural sections, each section comprising a plurality of spaced-apart layers of bonded aggregate of sufficient thickness to afford material structural strength, said layers being secured together by a less dense and more porous core of bonded fibrous material extending to the ends of the section and having exposed edge portions, the cores having edge grooves, and splines secured in said grooves of the floor and wall.

16. The combination in a wall structure of a support, a set of panels mounted thereon, each panel consisting of a prefabricated structural section comprising a plurality of spaced-apart layers of bonded aggregate of sufficient thickness to afford material structural strength, said layers being secured together by a less dense and more porous core of bonded fibrous material extending to the ends of the section and having exposed edge portions, the panels having registering bottom grooves, and registering vertically extending edge grooves with splines secured in the vertically extending edge grooves of the adjacent panels.

17. In a building suitable for a dwelling, a wall comprising a plurality of similar prefabricated structural sections comprising a complete wall unit, each section comprising a plurality of spaced-apart layers of bonded aggregate of sufficient thickness to afford material structural

strength, said layers being secured together by a less dense and more porous core of bonded fibrous material extending to the ends of the section and having exposed edge portions, the edges of said sections being interlocked, and said unit being of sufficient strength to carry the weight imposed upon said wall unit.

18. In a building suitable for a dwelling, a wall comprising a plurality of similar prefabricated structural sections comprising a complete wall unit, each section comprising a plurality of spaced-apart layers of bonded aggregate of sufficient thickness to afford material structural strength, said layers being secured together by a less dense and more porous core of bonded fibrous material extending to the ends of the section and having exposed edge portions, the adjacent edges of said sections having registering grooves, and splines permanently secured within said grooves.

19. A wall structure comprising prefabricated structural sections forming a complete wall structure, each section comprising a core of bonded fibrous material extending to the ends of the section and having exposed edge portions, and having a plurality of spaced-apart layers of bonded aggregate and cement of sufficient thickness to afford material structural strength to the section, said facing layers being more dense and less porous than the bonded fibrous core which secures them together, the bonded fibrous cores having grooves, and a spline device engaging registering grooves of the cores of successive sections.

said floor panels being grooved and splines secured within the registering grooves thereof.

15. The combination in a prefabricated structure, of a floor portion and a wall portion co-acting therewith, said portions each being formed of prefabricated structural sections, each section comprising a plurality of spaced-apart layers of bonded aggregate of sufficient thickness to afford material structural strength, said layers being secured together by a less dense and more porous core of bonded fibrous material extending to the ends of the section and having exposed edge portions, the cores having edge grooves, and splines secured in said grooves of the floor and wall.

16. The combination in a wall structure of a support, a set of panels mounted thereon, each panel consisting of a prefabricated structural section comprising a plurality of spaced-apart layers of bonded aggregate of sufficient thickness to afford material structural strength, said layers being secured together by a less dense and more porous core of bonded fibrous material extending to the ends of the section and having exposed edge portions, the panels having registering bottom grooves, and registering vertically extending edge grooves with splines secured in the vertically extending edge grooves of the adjacent panels.

17. In a building suitable for a dwelling, a wall comprising a plurality of similar prefabricated structural sections comprising a complete wall unit, each section comprising a plurality of spaced-apart layers of bonded aggregate of sufficient thickness to afford material structural

strength, said layers being secured together by a less dense and more porous core of bonded fibrous material extending to the ends of the section and having exposed edge portions, the edges of said sections being interlocked, and said unit being of sufficient strength to carry the weight imposed upon said wall unit.

18. In a building suitable for a dwelling, a wall comprising a plurality of similar prefabricated structural sections comprising a complete wall unit, each section comprising a plurality of spaced-apart layers of bonded aggregate of sufficient thickness to afford material structural strength, said layers being secured together by a less dense and more porous core of bonded fibrous material extending to the ends of the section and having exposed edge portions, the adjacent edges of said sections having registering grooves, and splines permanently secured within said grooves.

19. A wall structure comprising prefabricated structural sections forming a complete wall structure, each section comprising a core of bonded fibrous material extending to the ends of the section and having exposed edge portions, and having a plurality of spaced-apart layers of bonded aggregate and cement of sufficient thickness to afford material structural strength to the section, said facing layers being more dense and less porous than the bonded fibrous core which secures them together, the bonded fibrous cores having grooves, and a spline device engaging registering grooves of the cores of successive sections.
